VAPOR-ELECTRIC DEVICE

Peter L. Lenz, Edgewood, Pa., assignor to Westinghouse Electric & Manufacturing Company, East Pittsburgh, Pa., a corporation of Pennsylvania

Application April 21, 1938, Serial No. 203,362

6 Claims. (Cl. 250—27.5)

In the operation of vapor-electric devices, such as mercury arc rectifiers, it is customary to provide a high vacuum pump for maintaining the necessary vacuum for efficient operation of the device.

Heretofore considerable difficulty has been experienced because of the transfer of the working vapor between the vapor-electric device and the high vacuum pump which is usually of the so-called condensation or molecular vapor type, in which a pumping medium such as mercury, is vaporized and so directed as to entrap foreign gases which are to be removed from the vapor-electric device.

If the connections between the vapor-electric device and the pump are such that the working medium is transferred from the device to the pump, the pump soon becomes overloaded and is no longer operative, while on the other hand, if the working medium is transferred from the pump to the vapor-electric device, it also becomes inoperative and there is considerable danger that the removal of the working medium from the pump will permit the same to be overheated and damaged if not completely destroyed. In either event, it is necessary to shut down the apparatus and either remove or replace the working medium in the high vacuum pump.

Heretofore, many attempts have been made to maintain or automatically remove any excess working material out of the pump chamber. In the apparatus according to my invention, the pumping connection is so constructed as to substantially prevent any transfer of working medium in either direction between the vapor-electric device and the high vacuum pump.

According to my invention, this is accomplished by providing a two-part or V-type connection, each part comprising a passage preferably tubular in shape, one of said passages extending upwardly at a gentle slope from the vapor-electric device and the other extending upwardly from the pumping device. Preferably both of the pumping passages are of sufficient size to permit ready passage of non-condensable gases or vapor therethrough. These passages terminate in vapor traps which are supported adjacent to each other and the connection between the passages is made by a relatively small, preferably U-shaped tubular connection extending through the top of the traps and extending adjacent to the bottom wall of the trap and being separated therefrom, preferably by a distance substantially equal to the diameter of the U-shaped connection. Both of the upwardly extending or V passages, as well

as the vapor traps, are provided with cooling means for condensing any vapor entering therein either from the vapor-electric device or from the pump.

It is, accordingly, an object of my invention to provide a pumping connection which will substantially eliminate transfer of working medium in either direction between the vapor-electric device and its associated high vacuum pump.

It is a further object of my invention to provide a pumping connection having a relatively small intermediate passage therein.

Other objects and advantages of my invention will be apparent from the following detailed description taken in conjunction with the accompanying drawing, in which the single figure is an elevational view partly in section, of a vapor-electric device according to my invention.

In the illustrative embodiment of my invention, the vapor-electric device herein shown as 20 a mercury arc rectifier 1 having a mercury cathode 2 and a plurality of cooperating anodes 3, only one of which is shown herein, is connected to a suitable high vacuum pump 4 preferably of the vapor type by means of a two-part tubular 25 passage, one part 6 of the passage being connected directly to the chamber 1 to be evacuated and the other portion 7 of the tubular connection being connected directly to the high vacuum pump 4.

Both of these portions 6 and 7 are of considerable size, preferably of the order of approximately 3" in diameter, so that gases or vapors may readily enter therein. Each of the tubular passages terminates at the top end thereof in a suitable mercury or vapor trap 8 and 9. The traps 8 and 9 were preferably constructed in the form of a chamber connected to the end of the passages 6 and 7 and have a bottom wall level with the passage opening so that any material condensed therein will flow back into the vessel from which it originated.

In order to condense any vapors entering these connections 6 and 7, both the connections 6 and 7 and the vapor traps 8 and 9 are provided with suitable cooling elements herein illustrated as cooling coils 10 connected in good thermal contact with the exterior of the tubular connections 6 and 7 and with the exterior walls of the vapor traps 8 and 9. In order to provide a gas passage 40 between the legs 6 and 7 of the V connection, a tubular passage is provided between the vapor traps 8 and 9, said passage being relatively small with respect to the passages 6 and 7, the trap chambers 8 and 9 preferably being supported on 50 55

5 a common base plate 13 so that they are maintained in proximity to each other. Preferably this small diameter connection 8 is made of U-shape extending downwardly through the tops of each of the trap chambers 8 and 9 and extending adjacent to the bottom wall of the trap chambers preferably terminating a distance from the bottom wall approximately equal to the inside diameter of the connection 12.

10 10 In the operation of this device any mercury or other working vapor entering either of the larger connecting passages 6 or 7 will be cooled by the cooling device 10 applied to the exterior of the same, and most, if not all, of the vapors 15 will be condensed flowing back from the device from which it came. However, any vapor which is not condensed in the connections 6 and 7 will flow into the traps 8 and 9 and impinge against the cooled side walls and be condensed therein 20 flowing backward through the aforementioned tubular connections 6 and 7.

25 Because of the relatively small diameter of the interconnecting passage 12 and because of the proximity of the mouth of the passage 12 to a cooled surface, the working vapors do not enter the smaller passage 12, and consequently there is substantially no transfer of working medium between the vapor electric device 1 and its accompanying high vacuum pump 4.

30 30 While for purposes of illustration I have shown and described a specific embodiment of my invention, it will be apparent to those skilled in the art that many changes and modifications can be made therein without departing from the true 35 spirit of my invention or the scope of the appended claims.

I claim as my invention:

1. A pumping connection for connecting a 40 mercury vapor pump to a mercury arc device comprising a passage connected to said mercury arc device, a second passage connected to said mercury vapor pump, individual mercury traps connected to said passages, a U-shaped passage connecting said traps, said U-shaped passage being of smaller diameter than said first-mentioned 45 passages and extending into proximity with the bottom walls of said traps.

2. A pumping connection for connecting a 50 mercury vapor pump to a mercury arc device comprising a passage connected to said mercury arc device, a second passage connected to said mercury vapor pump, individual mercury traps connected to said passages, a U-shaped passage connecting said traps, said U-shaped passage

5 being of smaller diameter than said first-mentioned passages and extending into proximity with the bottom walls of said traps and cooling means applied to said first-mentioned passages and said traps.

3. A pumping connection for connecting a 10 mercury vacuum pump to an evacuated container comprising two oppositely sloping tubular passages of sufficient size to permit ready passage of gas and vapor therethrough, the lower end of one of said passages being connected to the evacuated container and the lower end of the other passage being connected to the mercury pump, individual condensing chambers connected to the upper ends of said passages, and a relatively small tubular passage connecting said condensing chambers. 15

4. An evacuating system for a vapor-electric device comprising a vapor pump, an upwardly inclined passage connected to said pump, an upwardly inclined passage connected to said vapor-electric device, each of said passages terminating in a vapor trap, means for cooling said passages and said traps to condense any vapor passing therein, means for supporting said traps in proximity to each other and a U-shaped passage extending into the top of each of said traps, said U-shaped passage being smaller in capacity than said first-mentioned passages. 20

5. An evacuating system for a vapor-electric 30 device comprising a vapor pump, an upwardly inclined passage connected to said pump, an upwardly inclined passage connected to said vapor-electric device, each of said passages terminating in a vapor trap, means for cooling said passages and said traps to condense any vapor passing therein, means for supporting said traps in proximity to each other and a U-shaped passage extending into the top of each of said traps, said U-shaped passage being smaller in capacity than 35 said first-mentioned passages, said U-shaped passage opening toward the bottom of said traps. 40

6. An evacuating system for a vapor-electric 45 device comprising a vapor pump, an upwardly inclined passage connected to said pump, an upwardly inclined passage connected to said vapor-electric device, each of said passages terminating in a vapor trap, means for cooling said passages and said traps to condense any vapor passing therein, means for supporting said traps in proximity to each other and a passage extending 50 between said traps, said passage being of smaller capacity than said first-mentioned passages.

PETER L. LENZ.
